UNITED STATES PATENT OFFICE.

GEORGE L. SUMMERS, OF HUNTINGTON, WEST VIRGINIA.

WINDOW-BEAD FASTENER.

1,171,276.

Specification of Letters Patent.

Patented Feb. 8, 1916.

Application filed April 26, 1915. Serial No. 23,951.

To all whom it may concern:

Be it known that I, GEORGE L. SUMMERS, a citizen of the United States of America, and a resident of Huntington, county of Cabell, State of West Virginia, have invented certain new and useful Improvements in Window-Bead Fasteners, of which the following is a full and clear specification, reference being had to the accompanying drawings, in which—

Figure 1 is a vertical sectional view through the sill of a window-frame showing my device in front elevation; Fig. 2 a vertical sectional view of a part of a window-frame and bead showing my device applied thereto, said section being taken on the line 2—2 of Fig. 1; Fig. 3 a horizontal section on the line 3—3 of Fig. 1; Fig. 4 a detail perspective view of the locking hook and its housing; and Fig. 5 a detail perspective view of the latch plate on the window-frame.

The object of this invention is to provide a simple device for removably locking the window bead in place, and it consists of certain novel features of construction hereinafter described and claimed.

In the drawing, *a* designates a tubular housing fitted in a vertical slot in the bead, *b* a sharpened hook being formed integral at each end of the housing at its outer edge and in position to be forced into the bead when the housing is fitted into the slot therein, to thereby anchor the housing in the slot. Both the inner and outer sides of the housing *a* are open, and adapted to vertically slide in the housing is a downwardly-turned hook *c* which projects beyond the inner edge of the housing and is provided on its outer edge with a projection *d* which slides within the housing. To guide the hook, I provide the same with a slot *e* and pass through the slots two or more transverse pins *f* supported on the vertical walls of the housing. This hook freely slides on the pins. It will be observed that the advantage in this form of guiding means is that it enables me to employ a housing which is open both at the outer side and at the inner side, that is, a simple tubular housing which is adapted to be fitted into a slot cut clear through the bead. Two or more of these hooks are affixed to the window bead at suitable points along its length, and to adapt the window-frame for engagement with the hooks, I cut a groove *g* in the face

of the window-frame coincident with each one of the hooks on the bead, and fasten in said groove, by means of screws *h*, a latch plate *i* whose outer face is flush with the face 60 of the window-frame and which is provided with a vertical slot *j*, through which the hook is inserted to enable it to gravitate into engagement with the lower edge of the slot. The latch plate is provided with longitudinal flanges *k* along its edge, which fit closely against the vertical walls of the groove *g*. The flanges *k* assist the screws in holding the latch plate securely in position, and the space between the flanges forms a housing 70 for the hook when the same is in engagement with the latch plate. It will be seen that engagement of the hook with the latch plate is obtained by simply allowing the hook to gravitate into engagement. By having the inner edge *l* of the hook beveled, it will be seen that a cam action is provided, the result of which is that the bead is drawn and held firmly against the window-frame. It will be seen that when the depending 80 hook thus cams the bead against the window frame, the entire strain of this action will be borne by the guide pins *f*. To remove the bead, it is simply necessary to insert the finger or a nail or other tool into 85 the outer part of the housing *a* and pull up on the finger lug *d*. In this way, the hook will be raised far enough to enable its depending beveled finger to be withdrawn through the slot *j* of the latch plate. 90

An advantage in terminating the finger lug *d* within the housing *a* is that accidental unlatching of the hook in manipulating the window sash or cleaning the window frame is thereby prevented. This location of the 95 finger lug will be advantageous also in that it avoids interference with the painting of the window frame.

Having thus described my invention, what I claim is:

1. In combination, a latch plate anchored in the window frame, a window bead provided with a vertical slot coincident with the latch plate, a tubular housing inserted in said slot, the inner and outer sides of this 105 housing being open and the housing being provided with means for anchoring it in the window bead, a gravitating latch inclosed in the housing, this latch being provided with an inwardly-extending, downwardly-turned hook adapted to engage said latch plate, the plate-engaging edge of the hook 110

being beveled downwardly and inwardly, and also with an outwardly-extending finger piece terminating at a distance from the outer face of the bead.

5. 2. In combination, a latch plate anchored in the window frame, a window bead provided with a vertical slot coincident with the latch plate, a tubular housing inserted in said slot, the inner and outer sides of this 10 housing being open and the housing being provided with means for anchoring it in the window bead and also with a latch guiding means extending across the housing, a gravi-

tating latch inclosed in the housing and slotted longitudinally for the passage therethrough of said guiding means, this latch being provided with an inwardly extending, downwardly-turned hook adapted to engage said latch plate, the plate-engaging edge of the hook being beveled downwardly and inwardly, and also with an outwardly-extending finger piece terminating at a distance from the outer face of the bead. 15 20

In testimony whereof I hereunto affix my signature.

GEORGE L. SUMMERS.
